FINGER RING

Robert Sciotti, 31821 Wellston,
Warren, Mich. 48093

Filed Apr. 23, 1971, Ser. No. 137,106

Term of patent 14 years

Int. Cl. D11—01

U.S. Cl. D45—10 B

FIG. 1 is a top plan view of a finger ring embodying my new design;

FIG. 2 is a side elevational view of the ring shown in FIG. 1;

FIGS. 3 and 4 are opposite end elevational views of the ring shown in FIG. 1; and

FIG. 5 is a perspective view of the ring shown in FIGS. 1-4.

I claim:

The ornamental design for a finger ring, as shown.
